R. DE SARRO

Des. 147,432

FIGURINE OR THE LIKE

Filed Aug. 5, 1946

Fig. 1.

Fig. 2.

Inventor:
Rodney De Sarro

UNITED STATES PATENT OFFICE

147,432

DESIGN FOR A FIGURINE OR THE LIKE

Rodney de Sarro, New York, N. Y.

Application August 5, 1946, Serial No. 132,291

Term of patent 14 years

(Cl. D29—23)

To all whom it may concern:

Be it known that I, Rodney de Sarro, a citizen of the United States, residing at New York, in the county of New York and State of New York, have invented a new, original, and ornamental Design for a Figurine or the like, of which the following is a specification, reference being had to the accompanying drawing, forming part thereof.

Fig. 1 is a side view of the figurine or the like, showing my new design.

Fig. 2 is a perspective view thereof.

I claim:

The ornamental design for a figurine or the like, as shown.

RODNEY DE SARRO.
